(57) **CLAIM**

The ornamental design for dual dock media player clock radio, as shown and described.

DESCRIPTION

FIG. 1 is a front perspective view of a dual dock media player clock radio, showing my new design;

FIG. 2 is a front view thereof;

FIG. 3 is a top view thereof;

FIG. 4 is a side view thereof;

FIG. 5 is a rear view thereof; and,

FIG. 6 is a bottom view thereof.

The broken lines in the drawings illustrate environmental material that forms no part of the claimed design.
